ESTERIFICATION OF POLYENE ACIDS

Charles D. Robeson, Rochester, N. Y., assignor to
Eastman Kodak Company, Rochester, N. Y., a
corporation of New Jersey

No Drawing. Application April 22, 1950,
Serial No. 157,622

17 Claims. (Cl. 260—410.9)

1 This invention relates to the esterification of polyene acids and is particularly concerned with methods of esterifying α,β -unsaturated polyene acids.

The treatment of long-chain polyene compounds such as α,β -unsaturated polyene acids is complicated by the inherent instability of such compounds and particularly by the lability of the unsaturated linkages. Thus many conventional chemical processes when employed with such polyene compounds cause isomerization of at least a portion of the polyene to an undesirable isomer by shifting of the unsaturation of the molecule.

It is accordingly an object of this invention to provide a method of esterifying polyene acids without affecting the unsaturation thereof.

It is a further object of the invention to provide a method of esterifying α,β -unsaturated polyene acids without substantial formation of α,γ -unsaturated isomeric esters.

Another object of the invention is to provide an improved method of esterifying vitamin A acid.

Another object of the invention is to provide a method of preparing α,β -unsaturated conjugated carotenoid polyene esters in good yield.

Another object of the invention is to prevent undesirable isomerization of vitamin A acid during esterification.

Another object of the invention is to provide a commercially feasible method of esterifying vitamin A acid without objectionable loss in yield due to formation of β,γ -unsaturated isomeric esters.

2 Other objects will be apparent from the description and claims which follow.

These and other objects are attained by means of this invention which comprises esterifying an α,β -unsaturated polyene acid by reacting, in a ketone, the acid to be esterified with an alkyl halide in the presence of a metal carbonate. By means of the esterification process embodying this invention, alkyl esters of α,β -unsaturated polyene acids are prepared in good yield without substantial formation of β,γ -unsaturated isomers thereof as normally occurs with conventional esterification processes as applied to such polyene acids.

The process embodying the invention is illustrated by the following reaction:

wherein R is an unsaturated hydrocarbon radical, R' is an alkyl group and X is a halogen atom. The α,β -unsaturated polyene radical remains unchanged during the reaction. This is in contrast to the course of a conventional acid-catalyzed esterification process wherein a substantial portion of the product obtained from an α,β -unsaturated acid is the β,γ -unsaturated isomer of compound II.

To illustrate, the esterification of vitamin A acid by the well-known acid-catalyzed esterification processes proceeds as follows:

The reaction product in such case consists of a mixture of the desired α,β -unsaturated conjugated polyene ester (Compound IV) and a β,γ -unsaturated conjugated isomer (Compound V) of the desired compound.

In the process embodying this invention, the esterification of vitamin A acid or other carotenoid polyene acids such as β -ionylidene acetic acid or similar α,β -unsaturated polyene acids gives substantially complete yields of the desired α,β -unsaturated alkyl ester (Compound IV) according to the following reaction:

Ketone
 Metal Carbonate

The esterification reaction embodying the invention can be carried out to produce any desired alkyl ester by choice of a suitable alkyl halide. Any alkyl halide can be employed to react with the α,β -unsaturated polyene acid being esterified including alkyl chlorides, bromides, iodides and fluorides, and aryl-substituted alkyl halides such as benzyl halides. The alkyl iodides are preferred because of their superior reactivity. In some cases when an alkyl chloride, fluoride or bromide is employed, it is desirable to incorporate a dissociable iodide such as an alkali-metal iodide or other inorganic iodide in the reaction mixture to promote the course of the reaction. Any alkyl ester can be prepared since any alkyl halide can be employed. Thus, typical alkyl halides include methyl halides, ethyl halides, allyl halides, propyl halides, butyl halides and the like. When a relatively inactive alkyl halide such as propyl chloride is employed, an alkali-metal iodide such as sodium, potassium or lithium iodide is desirably included in the reaction mixture although other dissociable iodides can be employed as the source of iodide ions. Allyl bromide can be satisfactorily employed alone, whereas an iodide is preferably employed in conjunction with ethyl bromide. When an alkyl iodide such as methyl or ethyl iodide is employed, the course of the reaction is not substantially affected by the presence or absence of an inorganic iodide.

The esterification reaction embodying the invention is carried out with the reactants in solution in a ketone and in the presence of a metal carbonate. Dialkyl ketones are desirably employed and particularly efficacious results are obtained by effecting the reaction in methyl ethyl ketone. Any metal carbonate can be employed which is effective to react with the polyene acid to form a metal soap. Alkaline metal carbonates including alkali-metal and alkaline earth carbonates are preferred with the alkali-metal carbonates such as sodium and potassium carbonates being desirably employed. Other metal carbonates which are entirely suitable include calcium carbonate and strontium carbonate, and these and other metal carbonates such as cupric carbonate can be employed in conjunction with such ketones as diethyl ketone, methyl ethyl ketone, acetone, methyl isobutyl ketone, cyclohexanone and the like.

The process embodying the invention is effective for esterifying in good yield and without substantial isomerization a wide variety of α,β -unsaturated polyene acids including α,β -unsaturated carotenoid polyene acids such as vitamin A acid, β -ionylidene acetic acid and the like; aromatic α,β -unsaturated polyene acids such as cinnamylidene acetic acid and the like; aliphatic α,β -unsaturated polyene acids such as pseudo-ionylidene acetic acid or 4,8,12-trimethyl-3,5,7,11-tridecaenoic acid, pseudo-vitamin A acid or 3,7,11,15-tetramethyl-2,4,6,8,10,14-hexadecaene-

25 oic acid, and the like; and similar α,β -unsaturated polyene acids.

The process embodying the invention further serves as a ready means for separating the α,β -unsaturated polyene mono-acids employed in practicing this invention from α,β -unsaturated polyene diacids, since such diacids do not esterify when subjected to the esterification process of the invention. Various α,β -unsaturated mono-acids are desirably prepared by partial decarboxylation of the corresponding diacid. In such cases, the monoacid product is usually contaminated with undecarboxylated diacid and it is desirable to effect separation of the mixture. The process of this invention provides a ready means of effecting such separation because, unlike acid-catalyzed esterification processes, the process embodying this invention esterifies only the mono-acid, to the substantial exclusion of the diacid. The unesterified diacid can thereafter be separated from the monoacid ester by washing the diacid out with aqueous alkali or by other well-known methods of separating acids and esters.

Thus, vitamin A diacids can be prepared by condensing β -ionylidene acetaldehyde with a β -methyl glutaconate diester or an isopropylidene malonate diester in the presence of a basic condensation catalyst, followed by saponification to form the diacid. These diacids are then decarboxylated to vitamin A acid by heating with a tertiary amine such as pyridine and a copper-bearing material such as copper or a copper salt. The resulting vitamin A acid is usually contaminated with vitamin A diacid. By subjecting the product to the process embodying this invention, the vitamin A acid is esterified without isomerization and the diacid remains unesterified and is readily removed by alkali washing.

The process of the invention is equally applicable for separating any of the other α,β -unsaturated polyene acids from admixture with diacids in similar fashion.

Certain preferred embodiments of the invention are illustrated by the following examples.

Example 1

A 0.5 g. portion of vitamin A acid was dissolved in 5 cc. of methyl ethyl ketone. To this solution was added 1.25 g. of ethyl bromide, 0.5 g. of potassium carbonate, and 0.005 g. of sodium iodide. The resulting reaction mixture was re-

5

fluxed for 2 hours at 87-89° C., cooled, diluted with 15 cc. of water and extracted with ether. The ether extract was washed successively with 0.5 N. potassium hydroxide solution and with water, dried over sodium sulfate and the ether removed by evaporation. The ethyl ester of vitamin A acid was recovered in 100% yield and had

$$E_{1\text{cm.}}^{1\%}(358 \text{ } \mu\mu) = 1170$$

Similar results were obtained with other carbonates such as cupric carbonate and sodium carbonate, and other ketones such as acetone and methyl isobutyl ketone.

Example 2

A solution was prepared by dissolving in 250 cc. of methyl ethyl ketone, 53 g. of 3,7,11,15-tetra-methyl-2,4,6,8,10,14-hexadecaenoic acid

$$(\text{pseudo-vitamin A acid, } E_{1\text{cm.}}^{1\%}(295 \text{ } \mu\mu) = 636)$$

To this solution was added 40 cc. of ethyl iodide and 40 g. of anhydrous potassium carbonate. The resulting reaction mixture was refluxed for 120 minutes on a steam bath, cooled, and extracted with ether. The ether extract was washed with 0.5 N. aqueous potassium hydroxide and with water, dried, and the ether removed by evaporation. The ethyl ester of pseudo-vitamin A acid obtained as product weighed 52 g. and had

$$E_{1\text{cm.}}^{1\%}(310 \text{ } \mu\mu) = 552$$

Example 3

The allyl ester of vitamin A acid was prepared by mixing together 0.5 g. of vitamin A acid, 5 cc. of methyl ethyl ketone, 0.2 g. of potassium carbonate, 1.39 g. of allyl bromide and 0.005 g. of sodium iodide, and refluxing the resulting mixture for 2 hours on a steam bath. The reaction mixture was worked up in the usual way to give 0.545 g. of vitamin A acid allyl ester having

$$E_{1\text{cm.}}^{1\%}(360 \text{ } \mu\mu) = 1125$$

a yield of 97.5%.

Example 4

The benzyl ester of vitamin A acid was prepared as follows. A 0.5 g. portion of vitamin A acid was dissolved in 5 cc. of methyl ethyl ketone, and to this solution was added 0.2 g. of sodium carbonate, 1.4 g. of benzyl chloride and 0.005 g. of sodium iodide. The reaction mixture was refluxed for 2 hours at 87-89° C., cooled, diluted with 50 cc. of water and extracted with ether. The ether extract was dried and the ether removed by evaporation to give 1.11 g. of the crude benzyl ester of vitamin A acid having

$$E_{1\text{cm.}}^{1\%}(360 \text{ } \mu\mu) = 405$$

Example 5

Fifteen grams of β -ionylidene acetic acid were dissolved in 100 cc. of methyl ethyl ketone, and 50 cc. of methyl iodide and 15 g. of potassium carbonate were added to the solution. The mixture was refluxed for 2 hours, an additional 25 cc. of methyl iodide added, and reflux was continued for one hour. The reaction mixture was filtered, ether was added to the filtrate, and the ether-filtrate mixture was washed successively with water, with 0.5 N. aqueous potassium carbonate and again with water. The ether layer was there-after separated and the ether removed by evapo-70 ration to give 14.7 g. of the methyl ester of β -ionylidene acetic acid as a pale yellow oil, a yield of 100%.

Example 6

The process embodying the invention is appli-75

6

cable for separating mixtures of a monoacid and a diacid. Thus, for example, β -ionylidene acet-aldehyde and a diester of β -methyl glutaconic acid are condensed in the presence of a basic condensation catalyst such as potassium hydroxide and the condensation product saponified to the diacid, γ -carboxy vitamin A acid, by refluxing with additional potassium hydroxide. This diacid is then heated in the presence of a tertiary amine, such as pyridine, and a copper-bearing compound, such as copper powder or copper acetate, to give vitamin A acid contaminated with undecarboxylated γ -carboxy vitamin A acid.

The separation of vitamin A acid from unchanged diacid is effected according to the following procedure. A 30.1 g. portion of a methyl ethyl ketone solution of crude vitamin A acid from the decarboxylation was mixed with 15 cc. of methyl iodide and 5.0 g. of potassium carbonate. The solution employed contained 3.58 g. of vitamin A acid having

$$E_{1\text{cm.}}^{1\%}(350 \text{ } \mu\mu) = 821$$

and a small percentage of contaminating diacid.

25 The resulting mixture was refluxed on a steam bath for 2 hours, diluted with water and extracted with ether. The ether and water extracts were separated; and the ether extract was washed to neutrality and the ether removed by evaporation. 30 The product, vitamin A acid methyl ester, weighed 3.8 g. and had

$$E_{1\text{cm.}}^{1\%}(352 \text{ } \mu\mu) = 782$$

The aqueous layer was acidified with 10% hydrochloric acid, extracted with ether and the ether removed by evaporation to give 0.25 g. of γ -carboxy vitamin A acid having an acid value of 272 and

$$E_{1\text{cm.}}^{1\%}(332 \text{ } \mu\mu) = 760$$

40 The process embodying the invention is applicable for esterifying other α,β -unsaturated polyene acids in good yield and without isomerization. Any of the alkyl esters, including aralkyl esters, can be prepared by use of an appropriate alkyl halide. Any metal carbonate capable of forming a metal soap with the acid being esterified can be employed, including such carbonates as calcium carbonate and strontium carbonate. Other ketones such as methyl isobutyl ketone, acetone and the like can also be employed, although methyl ethyl ketone is preferred for optimum results.

45 While the invention has been described in considerable detail with reference to certain preferred embodiments, it will be understood that these and other variations and modifications can be effected without departing from the spirit and scope of the invention as described hereinabove and as defined in the appended claims.

50 What I claim is:

1. The method of esterifying an α,β -unsaturated polyene acid without affecting the unsaturation thereof which comprises reacting, in a ketone, an α,β -unsaturated polyene monobasic organic acid and an alkyl halide in the presence of a metal carbonate.

55 2. The method of esterifying an α,β -unsaturated polyene acid without affecting the unsaturation thereof which comprises reacting, in a ketone, an α,β -unsaturated polyene monobasic organic acid and an alkyl halide in the presence of a basic metal carbonate.

60 3. The method of esterifying an α,β -unsaturated polyene acid without affecting the unsaturation thereof which comprises reacting, in a ketone, an α,β -unsaturated polyene monobasic

organic acid and an alkyl halide in the presence of an alkali-metal carbonate.

4. The method of esterifying an α,β -unsaturated polyene acid without affecting the unsaturation thereof which comprises reacting, in 5 methyl ethyl ketone, an α,β -unsaturated conjugated polyene monobasic organic acid and an alkyl halide in the presence of a metal carbonate.

5. The method of esterifying an α,β -unsaturated polyene acid without affecting the unsaturation thereof which comprises reacting, in a 10 ketone, an α,β -unsaturated polyene monobasic organic acid and an alkyl halide in the presence of a metal carbonate and a dissociable iodide.

6. The method of esterifying an α,β -unsaturated conjugated carotenoid polyene acid which 15 comprises reacting, in a ketone, a completely conjugated α,β -unsaturated carotenoid polyene monobasic organic acid and an alkyl halide in the presence of a metal carbonate.

7. The method of esterifying α,β -unsaturated conjugated vitamin A acid which comprises reacting, in a ketone, vitamin A acid and an alkyl halide in the presence of a basic metal carbonate.

8. The method of esterifying α,β -unsaturated conjugated vitamin A acid which comprises reacting, in a dialkyl ketone, vitamin A acid and an alkyl halide in the presence of a basic metal carbonate.

9. The method of esterifying vitamin A acid which comprises reacting, in methyl ethyl ketone, vitamin A acid and an alkyl halide in the presence of a metal carbonate.

10. The method of esterifying vitamin A acid which comprises reacting, in a ketone, vitamin A acid and an alkyl halide in the presence of a metal carbonate and a dissociable iodide.

11. The method of esterifying vitamin A acid which comprises reacting, in methyl ethyl ketone, vitamin A acid and an alkyl halide in the presence of an alkali-metal carbonate.

12. The method of esterifying vitamin A acid which comprises reacting, in methyl ethyl ketone, vitamin A acid and an alkyl halide in the presence of an alkali-metal carbonate and an alkali-metal iodide.

13. The method of preferentially esterifying an α,β -unsaturated polyene acid in admixture with a diacid which comprises reacting, in a ketone, a mixture of an α,β -unsaturated polyene monobasic organic acid and an α,β -unsaturated polyene diacid with an alkyl halide in the presence of a metal carbonate and thereby esterifying said α,β -unsaturated polyene acid without substantially esterifying said diacid.

14. The method of esterifying an α,β -unsaturated polyene acid which comprises reacting, in a dialkyl ketone, an α,β -unsaturated polyene monobasic organic acid having said α,β -unsaturation in conjugation with at least one other aliphatic unsaturated linkage, and an alkyl halide in the presence of a basic metal carbonate.

15. The method of esterifying an α,β -unsaturated conjugated carotenoid polyene acid which comprises reacting, in a dialkyl ketone, an α,β -unsaturated completely conjugated carotenoid polyene monobasic organic acid having said α,β -unsaturation in conjugation with at least one other aliphatic unsaturated linkage, and an alkyl halide in the presence of a basic metal carbonate.

16. The method of separating an α,β -unsaturated conjugated polyene monobasic organic acid from α,β -unsaturated polyene diacid which comprises reacting, in a ketone, a mixture of said acid and said diacid with an alkyl halide in the presence of a metal carbonate and thereby preferentially esterifying said acid, and separating the resulting ester of said acid from the unesterified diacid.

17. The method of separating vitamin A acid from admixture with vitamin A diacid which comprises reacting, in a ketone, a mixture of vitamin A acid and vitamin A diacid with an alkyl halide in the presence of a metal carbonate and thereby preferentially esterifying said vitamin A acid, and separating the resulting ester of said vitamin A acid from the unesterified vitamin A diacid.
